CLAIM

The ornamental design for a fuel cell adapter for tool, as shown and described.

DESCRIPTION

This application is related to the following commonly owned co-pending patent application: U.S. patent application Ser. No. 17/008,946, entitled "Combustion-Powered Fastener Driving Tool Fuel Cell Adapter,".

FIG. 1 is a top perspective view of a fuel cell adapter for tool of our new design.

FIG. 2 is a bottom perspective view of the fuel cell adapter for tool of FIG. 1.

FIG. 3 is a front view of the fuel cell adapter for tool of FIG. 1, the back view being a mirror image thereof.

FIG. 4 is a right side view of the fuel cell adapter for tool of FIG. 1, the left side view being a mirror image thereof.

FIG. 5 is a top view of the fuel cell adapter for tool of FIG. 1.

FIG. 6 is a bottom view of the fuel cell adapter for tool of FIG. 1.

FIG. 7 is a cross-sectional view of the fuel cell adapter for tool of FIG. 1, taken substantially along line 7-7 of FIG. 5; and,

FIG. 8 is a cross-sectional view of the fuel cell adapter for tool of FIG. 1, taken substantially along line 8-8 of FIG. 6. The broken lines in the drawings depict portions of the fuel cell adapter for tool that form no part of the claimed design.
